TABLE CONSTRUCTION

Warren S. Bellows, Shaker Heights, Ohio

Application October 20, 1932, Serial No. 638,695

5 Claims. (Cl. 311—108)

This invention relates to improvements in tables and more particularly to collapsible portable tables and is a continuation in part of my copending application Ser. No. 737,972, filed September 16, 1924.

Folding tables as heretofore constructed have usually been loosely put together and the legs have been commonly secured to the top which is the weakest part of the light weight portable tables. Inasmuch as such tables were unsteady when subjected to any great weight the use of such tables has been extremely limited and even their use as gametables has been objectionable. Not only have the legs been unsteady but furthermore the table top has been difficult to change where a different type of cover was desired or where the cover was to be removed for any desired purpose. These tables although primarily used for card playing are also suitably used for display purposes.

It is the principal object of this invention to provide a substantial folding table with a strong rigid frame holding a lightweight removable center which can be attractively ornamented and in which the table has foldable legs directly secured to the frame for greatest strength and simplicity of manufacture.

It is a further and more specific object of this invention to provide a portable table with a top supporting frame making a rabbeted joint with a lightweight cover, which frame is rigidly supported by a suitable leg construction, the cover reducing the weight without reducing the strength of the table.

Another object of the invention is to provide a tubular metal frame which may be welded or otherwise made into an integral piece to hold a separate non-metallic center for a portable table such as a card table which will have unusual rigidity and lightness.

Another object of the invention is to provide a portable table having a removable center portion which is supported in a suitable frame to which the legs are directly attached, the center being removable for recovering as desired and in which the frame may be decorated to more satisfactorily harmonize with other beautiful furniture with which the table may be used.

Various other objects and advantages of the invention will appear from the following description thereof taken in connection with the attached drawings which illustrate preferred forms of embodiment thereof and in which:

Figure 1 is a top plan view partially broken away of an improved type of table;

Figure 2 is a partial vertical section taken substantially on the line 2—2 of Figure 1 showing the details of construction;

Figure 3 is a bottom plan view of the table shown in Figure 1;

Figure 4 is a vertical section of a detail showing a slightly different form of construction;

Figure 5 is a plan view of a still further modified form of construction, partially in section;

Figure 6 is a partial vertical section taken substantially on the line 6—6 of Figure 5, and,

Figure 7 is a partial vertical section of a still further modified form of construction.

A portable type of table for card playing, display purposes, or otherwise and embodying certain features of my invention is more clearly shown in Figures 1 and 2. The table has, as its principal elements, a rigid frame 10, a separable center portion 16 and the frame is directly supported by collapsible legs 22.

The frame 10 may be made of wood, metal or other materials and if made of wood, may be made in two pieces 10 and 10a, the pieces giving an attractive wide marginal portion or border 11. If desired, the frame 10 may also be reinforced by suitable reinforcing strips 12 and 14 reinforcing the corners and acting as supports for the center respectively, as will be more fully explained hereafter.

The frame is supported directly by legs 22 which are held in open or extended position by suitable locking devices which will preferably hold the legs braced in two planes at right angles to each other. The braces 24 which may be pivoted on the reinforcing strips 12 extend from points spaced from the pivot 26 of the leg and will thus hold the legs in a desired position bracing the legs in both planes. As the legs are directly bracketed to the frame which may preferably be made the strongest part of the table without increase in weight, the frame will withstand extremely heavy loads for such a table yet without shaking or undue strain and even with the usual use as a card table, the table will not wobble if a player rests his hand on it. Other forms of leg constructions may of course be found suitable and the legs may be made in any desired shape and of metal or wood as desired.

The legs will fold about their pivots 26 and lie within the flange formed by the side 10 of the frame and the bottom of the marginal strip 10a. This facilitates close packing and carrying and prevents possibility of damage to the legs when the table is folded. It is to be understood that

any suitable clip may be used to hold the legs in the folded position if found desirable.

In order to detachably support the center 16 flush with the top of the frame 10, I prefer to 5 form an open rabbet groove 28 in the top of the frame to a depth corresponding to the thickness of the center support 18 and any desired cover 20 which it may carry to form the desired center 16. This rabbet 28 is thus arranged to receive 10 the center 16 and the center will be held in a detachable manner to the frame 10 by suitable fastening means 30 which project at spaced intervals through the frame. Screws, bolts, etc., and other materials may be used for this purpose, 15 making possible the easy removability of the cover.

When in position, the center is preferably flush with the marginal edge 11 which may also be ornamented or otherwise decorated to correspond 20 with the cover material. The braces 14 may be used to additionally support the center 16 to hold it more rigid throughout its length. Obviously, these strips are unnecessary where the center 16 is inherently strong enough to accomplish the 25 purpose. The center may be of any desired material but is preferably not metallic for lightness, and laminated wood structures are satisfactory.

The removable center has many advantages in 30 that the table may be constructed with any desired frame and the center may be inserted at a subsequent time and is substantially a separate entity. The center may have, for example, a transparent cover and advertising or ornamental matter placed under it for specific uses. Cover 35 materials of treated fabrics or celluloid may be used which are not stained or which can be washed repeatedly without injuring the decorative effect on the center portion. It is also possible to have a plurality of covers for a single frame, each cover 40 for example having a game, chart, or similar design on the surface so that the table will have many separate uses.

If desired, the table top may have a narrow border 11a by slightly changing the shape of the 45 supporting frame 10b. In Figure 4, for example, I have shown a solid block 10b in which the channel or rabbet portion 28 has been cut out leaving the exposed narrow marginal portion. In such a construction the support 18 for the center 50 16 may similarly be covered with a suitable cover 20 of fabric or other flexible material whether it be transparent or otherwise. In this construction the legs 22a are similarly secured to the frame 10b so that a strong bond may be made 55 between the frame and the legs rather than in the prior forms of constructions in which the legs were secured to the center portion which is normally the structurally weakest part of the table.

If desired, the table may be made with a tubular metal frame more clearly shown in Figure 6. The frame 30 may be of any particular cross-sectional configuration and it preferably is provided with some projecting means forming a support for the removable center portion. One form 65 of construction includes angle brackets 32 which may be bolted or spot welded to the frame 30 in any desired fashion and either be bolted or otherwise removably secured by detachable means 33 to the removable center portion.

70 The cover 20 is preferably secured to the support 18 by tacks 34, cement or other securing means before the center portion is secured to the frame. This makes separate handling of the center possible and facilitates the stretching of 75 the cover in place. After the cover is secured

to the center portion, and the center portion secured in the frame, the contact between the cover and frame will prevent loosening and will give a very attractive joint.

It is also possible to apply two or more respective covers 20 and 20a to the support 18, one of which may be transparent and the other of which may be ornamental. 80

On large tables it may be found desirable to employ reinforcing rods 36 which may, if desired, project through the frame at right angles and be spaced from the center support 18 by additional angle brackets 38. Such a reinforcing means accomplishes two purposes in that it not only prevents expansion of the frame but also cooperates 90 to support the center which may be structurally weak.

Tubular frames made of steel for example, may be readily pressed to any desired form or shape, and it may be found preferable to use a construction such as shown in Figure 7. In this instance the metal frame 40 is provided with a narrow ledge or marginal portion 41 and has a suitable channel 42 forming a rabbet which will receive the center support 18 and the cover 20 and if desired a second cover 20a as in the previous form. This is very similar to the rabbet construction of 100 Figure 4. The legs 22 which may be of steel or wood and of any desired shape are similarly secured to an inner flange 43 of the frame and only 105 indirectly support the center and cover through the frame member. Such a table has considerable rigidity and may be preferred from a standpoint of lightness to the wooden frame tables, especially when a light laminated or moulded product 110 is used for the support 18.

The center support 18 and covering 20, if any, are intended to fit closely within the rabbet of the frame. Preferably the covering will overlap the edge of the center support and then be 115 held in firm contact between the support 18 and the bracket to which it is secured as well as being secured directly to the support 18. While this is not essential inasmuch as the cover may be secured to the center support in any other desired manner, it is nevertheless an additional feature which prevents the cloth from being inadvertently removed from the table. 120

As is indicated, it is possible to have either the very narrow border table or the wide border table 125 depending entirely on the selection of frame members, and the center support may be demountably held by any desired means such as bolts, or nuts, as shown in Figure 6, or by screws 44 as shown in Figure 7. The frame, after being pressed into 130 proper shape to give a pleasing outer appearance, can then be welded in any desired manner to give an integral structure. The table will thus be rigid, strong, ornamental and of light weight and may be made by simple manufacturing methods. 135

While I have shown a preferred form of embodiment of my invention, I am aware that other modifications may be made thereto and I therefore desire a broad interpretation of my invention within the scope and spirit of the description herein and of the claims appended herein-after. 140

I claim:

1. In a portable table of the type described, a rim having an offset edge, a plurality of foldable legs supporting said rim, a detachable center portion, and means to removably secure said detachable center portion to the offset edge of said rim, a cover for said center portion, means to secure said cover to said center portion where- 145

- by said center portion and cover may be removed as an integral whole, and a second cover on said center portion, said second cover being flexible and transparent. 80
- 5 2. A folding portable table of the class described, comprising a supporting rim having an open rabbet groove in the top inner edge thereof, a lightweight center portion for said table and supported in said rabbet in a substantially flush relation, detachable means extending into said center portion and projecting through a part of said rim to demountably retain said center portion in position, and a plurality of removable covers on said center portion and extending between 85
- 10 15 said center portion and said rim in said rabbet, one of said covers being flexible and transparent, and legs pivotally secured directly to said rim and supporting said rim independently of said center portion. 90
- 20 3. A folding portable table of the class described comprising a hollow metallic supporting frame, a ledge extending from said frame and forming a support on the inner edge thereof, a lightweight center portion for said table supported 95
- 25 on said ledge, securing means extending through said ledge and contacting with said center portion to demountably retain said center portion in said frame, a reinforcing rod extending across the frame to support the center portion, a flexible transparent cover on said center 100
- 30 35 portion and secured thereto, and foldable legs secured to said rim and supporting said rim independently of said center portion. 105
4. A portable, light weight and rigid game table having a hollow tubular metallic rim portion supported by collapsible legs, said rim portion 110
